US0D1105046S

(12) **United States Design Patent** (10) Patent No.: **US D1,105,046 S**
(45) Date of Patent: ** Dec. 9, 2025

(54) **CASE FOR MOBILE PHONE**

(71) Applicant: **Shenzhen Lanhe Technologies Co., Ltd.**, Shenzhen (CN)

(72) Inventors: **Zhijun Liang**, Guangdong (CN); **Churong Tang**, Guangdong (CN); **Haisong Qiu**, Guangdong (CN); **Lei Wang**, Guangdong (CN)

(73) Assignee: **SHENZHEN LANHE TECHNOLOGIES CO., LTD.**, Shenzhen (CN)

(**) Term: **15 Years**

(21) Appl. No.: **29/877,715**

(22) Filed: **Jun. 12, 2023**

(51) LOC (15) Cl. **03-01**

(52) U.S. Cl.

USPC **D14/250**

CLAIM

The ornamental design for a case for mobile phone as shown and described.

DESCRIPTION

FIG. 1 is a front perspective view of a case for mobile phone showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view thereof, shown in a state of use.

The broken lines and unshaded surfaces depict portions of the case for mobile phone that form no part of the claimed design.

1 Claim, 9 Drawing Sheets
